UNITED STATES PATENT OFFICE.

JAMES V. WASHBURNE, OF FULTON, NEW YORK.

LOOSE-LEAF BINDER.

1,094,951.

Specification of Letters Patent.

Patented Apr. 28, 1914.

Application filed February 5, 1913. Serial No. 746,409.

To all whom it may concern:

Be it known that I, JAMES V. WASHBURNE, of Fulton, in the county of Oswego, in the State of New York, have invented new and useful Improvements in Loose-Leaf Binders, of which the following, taken in connection with the accompanying drawings, is a full, clear, and exact description.

This invention relates to certain improvements in loose leaf binders adapted to be used for temporarily or permanently binding loose sheets which have been previously perforated near one edge for receiving the tongues of one of the binding members.

15 The main object is to provide an extensible two-piece tongue binder in which one member interlocks with and conceals the ends of the tongues of the other member so that both members, including the tongues, 20 lie flat against opposite faces of the outermost leaves, thereby avoiding objectionable projections which would interfere with the handling or filing of the bound leaves or records. In other words, I have sought to 25 produce a simple and comparatively inexpensive sheet metal binder composed of two members, one of which is provided with end tongues of any suitable length adapted to pass through the apertures in the leaves and 30 to interlock with the slotted ends of an opposed member in such manner that the ends of the tongues will be concealed by the main body of the slotted member.

A further object is to enable the binding 35 members to be easily and quickly adjusted so as to bind and hold the sheets firmly one upon the other and also permitting similar sheets to be readily added to or withdrawn from the binder as may be required.

40 Other objects and uses will be brought out in the following description.

In the drawings—Figure 1 is a perspective view of a series of leaves shown as bound together by my improved binder. Fig. 2 is a longitudinal sectional view of the same binder taken on line 2—2, Fig. 1, showing the leaves in dotted lines. Fig. 3 is a perspective view of both parts of the binder showing the manner of interlocking them 45 at one end after the tongues have been inserted through the apertures in the leaves preparatory to final adjustment for binding such leaves together. Fig. 4 is a perspective view of the slotted binding member. 50 Fig. 5 is a transverse sectional view through the same binder as adjusted for use. Fig.

6 is an enlarged transverse sectional view through one end of the slotted member and adjacent end of the tongue of the other member interlocked therewith taken on line 60 6—6, Fig. 1, showing one form of detent for holding said members in interlocking engagement. Fig. 7 is a sectional view similar to Fig. 6 showing a slightly modified form of detent.

This binder comprises a pair of opposed, comparatively thin, sheet metal plates or bars —1— and —2—, one of which, as the bar —1—, constitutes what may be termed a base plate and is substantially flat and provided with a pair of end tongues or bendable arms —3— which are normally bent at substantially right angles to the main body and adapted to pass through corresponding apertures, as —a—, near one 65 edge of the sheets as —A— which are to be bound as shown more clearly in Figs. 1 and 2. The plate or bar —2— is also substantially flat and provided with end slots —4— and —5— spaced apart a distance less than the space between the tongues —3— at their junctions with the main body of the plate —1—, one of the slots, as —4—, being preferably formed wholly within the marginal edges of the plate —2—, while 70 the slot —5— preferably extends laterally through one of the longitudinal edges of said plate. The tongues —3— may be of any desired length according to the number of sheets which is desired to be bound 75 but of less width than the main body of the plate —1— and integrally united to the centers of the ends thereof, the entire plate or bar —1— being preferably made of soft brass or equivalent easily bendable 80 material although the main body is preferably reinforced by lengthwise stiffening ribs —6— pressed up therefrom near the longitudinal edges. The slot —4— is of substantially the same size as the cross sectional 85 area of the tongue —3— which it is adapted to receive, sufficient clearance being left to allow the plate —2— to slide freely on its tongue. The slot —5— is of substantially the same width lengthwise of the bar 90 —2— as the thickness of the other tongue —3— which it is adapted to receive but, owing to the fact that this slot —5— extends through one of the longitudinal edges of the bar and that this bar —2— is of greater 95 width than the tongues, it forms a lip —7— at the outer end of the slot —5— capable 100 105 110

of being overturned upon the tongue —3— with which it is adapted to interlock as shown in Fig. 7 so as to hold both of the members of the binder in operative relation when placed in operative position upon the leaves. In some instances, however, this lip may be provided with an integral projection —7'— pressed up therefrom as shown in Fig. 6 for the purpose of engaging one of the edges of the adjacent tongue and frictionally holding the binding members in operative position, thereby serving a purpose similar to that of the overturned lip —7—.

15 In assembling the binder upon the sheets, which are previously perforated near one edge a distance apart corresponding to the space between the tongues —3— when bent at right angles to the main body of the plate, 20 said tongues are inserted through the apertures from one side of the stacked sheets after which the plate —2— is placed in operative position upon one of the tongues —3— and then both tongues are bent inwardly and downwardly toward each other upon the opposite side of the stacked sheets after which the plate —2—, which has been 25 previously interlocked with the adjacent tongue —3— is carried forwardly toward the other tongue, thereby facilitating the bending of the adjacent tongue flatwise against the upper side of the sheets and, as soon as the plate —2— is brought flatwise against the adjacent sheet, its lip —7— is 30 slipped under one edge and beyond the opposite edge of the opposite tongue —3—, thereby firmly locking the two binding members to each other and causing the main body of the plate —2— to conceal the ends 35 of the tongue —3— as shown more clearly in Figs. 1 and 2.

When the binding members are assembled in the manner just described, the end of the lip —7— may be bent over and upon the 40 opposite side of the adjacent tongue —3— to prevent lateral displacement of the plate —2— or when the lip is provided with the raised projection —7'—, the latter serving the same purpose in preventing the displacement 45 of the member —2— from interlocking engagement with the member —1—. It will be observed that the binding member —2— is of substantially the same length as the main body of the plate —1— or as the distance 50 between the tongues —3— when the latter are bent at right angles to said main body.

What I claim is:

1. A loose leaf binder comprising co- 60 operative flat sheet metal plates, one of said

plates having end tongues adapted to be passed through apertures in the leaves and overturned upon the outermost leaf, the other plate having one end interlocked with one of the tongues and its other end provided with a lip inserted under the other tongue, the main body of the latter plate covering the ends of both tongues. 65

2. A loose leaf binder comprising a pair of substantially flat sheet metal plates, one 70 of the plates having end tongues adapted to pass through apertures in the leaves, the other plate having one end interlocked with one of the tongues and its other end provided with an open sided slot for receiving 75 the other tongue and slidably interlocked therewith by lateral movement, the ends of the tongues being covered by the main body of the second named plate when adjusted for use. 80

3. A loose leaf binder comprising co-operative flat sheet metal plates, one of said plates having end tongues adapted to be passed through apertures in the leaves and overturned upon the outermost leaf, the 85 other plate having one end interlocked with one of the tongues and its other end provided with a lip inserted under the other tongue, the main body of the latter plate covering the ends of both tongues, and 90 means tending to hold said lip in operative position.

4. A loose leaf binder comprising co-operative flat sheet metal plates, one of said plates having end tongues adapted to be 95 passed through apertures in the leaves and overturned upon the outermost leaf, the other plate having one end interlocked with one of the tongues and its other end provided with a lip inserted under the other 100 tongue, the main body of the latter plate covering the ends of both tongues, said lip adapted to be return bent against the adjacent tongue to prevent disengagement of 105 said lip and tongue.

5. A loose leaf binder comprising co-operative sheet metal plates, one of said plates having end tongues and the other plate having one end adapted to be interlocked with one of the tongues and its other end provided with an open-sided slot forming a lip adapted to be inserted under the other tongue, said tongue having a lateral sliding engagement in said slot. 110

In witness whereof I have hereunto set 115 my hand this 3rd day of February, 1913.

JAMES V. WASHBURN.
